Des. 218,980

Patented Oct. 20, 1970

218,980

LAP SUPPORTED BOOK STAND

William J. Balkus, 8584 Littlefield,
Detroit, Mich. 48228

Filed June 25, 1969, Ser. No. 17,876

Term of patent 14 years

Int. Cl. D6—01

U.S. Cl. D33—3

FIG.1

FIG.5

FIG. 1 is a perspective view of the book stand showing the new design;

FIG. 2 is a front view of the lap supported book stand;

FIG. 3 is a side view of the lap supported book stand;

FIG. 4 is a bottom view of the lap supported book stand;

FIG. 5 is a top or plan view of the lap supported book stand.

The side of the stand not shown is a mirror image of the side shown.

I claim:

The ornamental design for a lap supported book stand, substantially as shown and described.
